United States Patent Office

Des. 194,055
Patented Nov. 13, 1962

194,055

DUSTPAN

Clara Virginia Eicholtz, Midland, Mich., assignor to The Dow Chemical Company, Midland, Mich., a corporation of Delaware

Filed June 20, 1962, Ser. No. 70,631

Term of patent 14 years

(Cl. D44—18)

Fig. 1

Fig. 2

Fig. 3

Fig. 4

Fig. 5

FIGURE 1 is a top plan view of a dustpan of my new design;

FIGURE 2 is a side elevational view thereof;

FIGURE 3 is a bottom view thereof;

FIGURE 4 is a cross-sectional view thereof taken along the reference line 4—4 of FIGURE 1; and

FIGURE 5 is a cross-sectional view thereof taken along reference line 5—5 of FIGURE 1.

I claim:

The ornamental design for a dustpan, as shown.
